UNITED STATES PATENT OFFICE

122,301

DESIGN FOR A DISPLAY UNIT FOR SPARK PLUG TESTING AND CLEANING DEVICES

Robert L. Reeves and Raymond W. Allen, Akron, Ohio, assignors to The Firestone Tire & Rubber Company, Akron, Ohio, a corporation of Ohio

Application January 19, 1940, Serial No. 89,586

Term of patent 14 years

To all whom it may concern:

Be it known that we, Robert L. Reeves and Raymond W. Allen, citizens of the United States, residing at Akron, in the county of Summit and State of Ohio, have invented a new, original, and ornamental Design for a Display Unit for Spark Plug Testing and Cleaning Devices, of which the following is a specification, reference being had to the accompanying drawing, forming part thereof, in which:

Figure 1 is a perspective view of a display unit

for spark plug cleaning and testing devices showing our new design;

Figure 2 is a rear elevation of the unit shown in Figure 1; and

Figure 3 is a side elevation of the display unit of Figure 1.

We claim:

The ornamental design for a display unit for spark plug testing and cleaning devices, as shown.

ROBERT L. REEVES.
